TWISTER

Filed Nov. 28, 1928

J.E. DeCourcy Inventor

by *Lacey Lacey*, Attorney

UNITED STATES PATENT OFFICE

JOHN E. DE COURCY, OF WORCESTER, MASSACHUSETTS

TWISTER

Application filed November 28, 1928. Serial No. 322,413.

The invention relates to the art of spinning and more particularly to means for twisting slivers or yarns in the formation of threads or cords.

5 The present invention enables the winding of a greater amount of thread upon a spool or bobbin than is possible by the present cap, ring or flier method, since the bobbin is situated some distance from the twister and is not limited in capacity thereby.

While the drawing illustrates a preferred embodiment of the invention, it is to be understood that in adapting the means to meet specific needs and requirements, the design 15 may be varied and changes in the minor details of construction may be resorted to within the scope of the invention as claimed, without departing from the spirit thereof.

For a full understanding of the invention 20 and the merits thereof, reference is to be had to the following description and the drawing hereunto attached, in which:

Figure 1 is a diagrammatic view illustrative of the invention in conjunction with a 25 spinning frame.

Figure 2 is a central, longitudinal sectional view of the twister.

Corresponding and like parts are referred to in the following description and designated 30 in both views of the drawing by like reference characters.

Referring to Figure 1 of the drawing the numeral 1 denotes the back rolls, 2 the front rolls and 3 the carrier rolls of a spinning frame. The usual dolly or take up rolls are indicated at 4, and 5 designates the bobbin upon which the thread or yarn is wound. The numeral 6 designates generally the 35 twister which constitutes the present invention, the same being located between the delivery rolls 2 and the take up rolls 4. The twister may be mounted upon the thread board of a spinning frame, or in any preferred or determinate way, according to the 40 design or construction of the spinning frame with which it is associated.

The twister comprises a rotatable body and a mount therefor which is adapted to be attached to the spinning frame. The body 45 includes a hub 7, a funnel 8 and a handle 9.

A passage 10 is formed in the hub 7 and handle 9 and extends diagonally from the apex of the funnel 8 through a side of the handle 9. A second passage 11 is in communication with the passage 10 and extends through the handle 9 at an opposite inclination to the passage 10.

The outer end of the passage 11 terminates centrally of the handle 9. A block 12 of porcelain or analogous material is set in an opening, or recess, formed in the end of the handle 9 and the passage 11 extends therethrough. A block 13, of porcelain or analogous vitreous material, is set in an opening or recess formed in the side of the handle 65 and a groove 14 formed in the outer side thereof is in communication with the passages 10 and 11. The blocks 12 and 13 resist the wear of the thread or yarn passing therethrough. The inner wall of the funnel 8 is 70 rough either by a lining applied thereto, or by flutes or fine grooves, the purpose being to engage the sliver or yarn and effect a twisting thereof when the device is in active operation. Channels or grooves 15 are formed in the outer surface of the hub 7 to form races for ball bearings 16. A retainer ring 17 holds the balls 16 in place and is preferably of sectional formation to admit of the parts being readily assembled.

The mount or supporting frame for the twister body comprises complementary plates 18 and 19 and a filler 20. These parts when assembled are secured by means of bolts 21 or like fastening means. The outer portion 85 of the hub 7, the ball bearings 16 and the retainer ring 17 are confined between the plates 18 and 19. The twister may be secured to the spinning frame or other supporting means in any determinate way. The twister body may 90 be rotated in any manner and is provided with an annular seat or whorl 22 to receive the usual drag band, not shown, generally employed for rotating the bobbins or spools of spinning frames. In the preferable construction the component parts of the twister body are of integral formation. The passages 10 and 11 are straight and oppositely inclined and open through a side of the handle 9 intermediate the ends thereof.

The sliver or yarn, not shown, is drawn through the passages 10 and 11 by means of a needle or slender wire formed into a hook at one end. The sliver or yarn passes between the pairs of rolls 1, 2, 3 and 4 and through the funnel 8 and passages 10 and 11 and is attached to the bobbin or spool 5 to be wound thereon. During the passage of the sliver or yarn through the twister body, some twist is imparted thereto by reason of the corrugated formation of the funnel and the inclined arrangement of the passages 10 and 11. The bobbin or spool 5 is located some distance from the twister, hence is adapted to receive a great amount of thread considerably in excess of that adapted to be wound upon the bobbin by the usual method employing a cap, ring or flier twister. When it becomes necessary to stop a twister to piece up a broken end, or for other cause the handle 9 is grasped. At this time the drag band slides over the whorl 22 in a manner readily understood. Any one of the twisters may thus be temporarily stopped without throwing the frame out of action as a whole.

The term funnel as applied to the part 8, includes a bell, or analogous flared part. It is observed that while the passages 10 and 11 are shown straight they may be curved or have any preferred form.

Having thus described the invention, I claim:

1. A twister comprising a supporting frame, and a twister body rotatably mounted therein and comprising a centrally disposed hub, a funnel at one side of the hub and a handle at the opposite side of the hub aligned axially with the funnel, and having oppositely inclined passages formed therein and opening through a side of the handle and through the outer end thereof and in communication with the funnel at the apex thereof, the funnel being widely flared whereby the angle of the hub and the funnel will define a groove to receive a driving belt.

2. A twister comprising a supporting frame including complemental side plates and a bearing held by and between said plates, a twister body comprising a hub fitted between the side plates and journaled in said bearing, a funnel projecting axially from one side of the hub and widely flared whereby to receive a driving belt adjacent the side of the hub, a handle projecting axially from the opposite side of the hub and having oppositely inclined passages formed therein leading from the apex of the funnel through a side and the outer end of the handle, and wear-resisting blocks in said passage at the side of the handle and at the outer end thereof.

In testimony whereof I affix my signature.
JOHN E. DE COURCY. [L. s.]
